[57] CLAIM

The ornamental design for a container for flowers, pencils, jewelry or the like, as shown and described.

DESCRIPTION

FIG. 1 is a top perspective view of a container for flowers, pencils, jewelry or the like showing my new design;

FIG. 2 is a top plan view thereof;

FIG. 3 is a side elevational view thereof, the undisclosed sides being similar to the side shown; and

FIG. 4 is a bottom plan view thereof.

FIG. 2

FIG. 1

FIG. 3

FIG. 4
